UNITED STATES PATENT OFFICE.

JAMES BRUCE, OF NEW YORK, N. Y.

DIVING APPARATUS.

SPECIFICATION forming part of Letters Patent No. 361,925, dated April 26, 1887.

Application filed January 13, 1887. Serial No. 224,256. (No model.)

To all whom it may concern:

Be it known that I, JAMES BRUCE, a subject of the Queen of Great Britain, residing at New York, in the county and State of New York, 5 have invented new and useful Improvements in Diving Apparatus, of which the following is a specification.

This invention relates to improvements in diving apparatus, as set forth in the following 10 specification and claims, and illustrated in the accompanying drawing, which represents a side elevation, partly in section, of a diving apparatus.

The letter A represents a helmet or hood 15 adapted to sit over the head of a diver. A sight-hole, B, protected by a transparent material—such as glass—enables the diver to see objects outside of the helmet. An inlet-tube, C, supplies air to the interior of the helmet 20 A, so that the diver can breathe. By providing the inlet-tube C with a flaring mouth, D, the entry of air into the inlet-tube is facilitated. The spent air is led from the helmet A by the 25 exit or outlet tube E. A supply of heat—such as a stove or lamp, G—is applied at or near the top or free end of the exit-tube E, so that said portion of the exit-tube E becomes heated and the air contained therein expands, and consequently rises, its place being taken up 30 by air which rises from the helmet through said tube E. Since nature does not allow a vacuum, fresh air passes into the helmet through the tube C, and a circulation of air will therefore take place from the mouth D, 35 through tube C, helmet A, and tube E. If

the helmet rests upon the shoulders of the diver, this circulation will still continue and not be disturbed by the action of the lungs of the diver. The foul air exhaled by the diver follows the current of air induced through the 40 tube E by the expansion of the air at or near the top end of said tube, and a constant supply of fresh air is maintained in the helmet. By enlarging the portion F of the exit-tube at which the heat is applied said heat is enabled to act 45 on a larger surface, thus accelerating the outflow of air from the exit-tube. By this circulation of air the space in the helmet A is constantly supplied with fresh air. The free ends of the inlet-tube C and exit-tube E are secured 50 to any suitable support—such, for example, as a float or boat, H.

What I claim as new, and desire to secure by Letters Patent, is—

1. The combination, with a helmet or hood, 55 A, of an inlet-tube, C, an exit-tube, E, and means for heating the free end of the exit-tube, substantially as set forth.

2. The combination, with a helmet or hood, 60 A, of an inlet-tube, C, an exit-tube, E, provided with an enlargement, F, and means for supplying heat at said enlargement F, substantially as set forth.

In testimony whereof I have hereunto set my hand and seal in the presence of two subscribing witnesses.

JAMES BRUCE. [L. S.]
